Shoe presser having a standard having an arcuate section and a bifurcated section and a handle for operating the device.

01. SIZE 10 1/2

UNITED STATES PATENT OFFICE

2,137,946

SHOE PRESSER

Max W. Miller, Newport, Ky.

Application January 24, 1938, Serial No. 186,686

1 Claim. (Cl. 12—17)

My invention relates to shoe pressers by which pressure may be applied to portions of shoes to maintain certain parts thereof together while being operated upon.

5 One of the principal objects of my invention is to provide a shoe press equipped with means to force the shank portion of a shoe into intimate contact with the last which it contains and at the same time force the upper edge of the 10 upper material or sole towards the position in which it is to be secured to the shank and equipped with means for securely holding the parts together under pressure during the setting of cement applied between the parts, thus eliminating the use of nails and the like.

Another object of my invention is to provide a device of the above described character which is simple in construction, durable in use, efficient in operation and economical in manufacture.

20 Other objects and advantages will be apparent from the following description, appended claim and annexed drawing.

Referring to the drawing wherein like reference characters designate like parts throughout the several views:

Fig. 1 is a side elevation of my invention.

Fig. 2 is a sectional view taken on the line 2—2 of Figure 1.

30 In practicing my invention I provide a support 5 of typical construction having mounted thereon an arcuate shaped standard 6 of U-shaped configuration. The upper end of said standard is bifurcated and receives therein a pressure lever 7 pivotally mounted on a shaft member 8 journaled in bifurcated sections 9.

35 One end of the pressure lever 7 is fashioned with an arcuate section 10 working between the sections 9. Said arcuate section is fashioned at one end on the periphery thereof with teeth 11 engageable by a dog 12 pivotally mounted on the standard 6 adjacent the bifurcated sections as at 13, said dog being equipped with a release handle 14. The opposite end of the pressure 40 lever 7 is formed with a handle 15 whereby the lever is manually operated.

45 Mounted on the support or table 5 is a shoe last 16 for receiving thereon a shoe 17, as illustrated in dotted lines, interposed between said last and the lower end of the arcuate section 10 of the pressure lever. Interposed between the last 16 and the bifurcated sections 9 for engagement by the arcuate section 10 of the pressure lever is a pressure arm 18 adjustably carried by 50 the intermediate section of the standard 6. The

outer end of the pressure arm 18 is fashioned on the lower face thereof with a dove-tailed section 19 receiving therein a body of resilient material 20, for instance rubber. The opposite end of said arm extends through a tapered slot formed in the standard 6 whereby to permit adjustment relative thereto.

5 The lower end of the arm 6 is formed with a downwardly extending section 21 having a lug 22 formed thereon for maintaining the section 21 within a slot 23 formed in the support where- 10 by the arm is secured against movement during the operation of the device. However, by moving said arm towards said last, the same may be disengaged from said support when not in use. 15

In operation, when a shoe is placed over the last 16, the shank is treated with cement and a sole positioned thereon and the arm 18 ad- 20 justed thereabove to position the resilient mate- 25 rial 20 in engagement with the end of the sole. 20

In this position the pressure lever is operated to cause the lower end of the arcuate section 10 to engage the upper face of the arm 18 and force the same downwardly, thereby applying pres- 25 sure on the sole for effecting a proper cementing 25 of the sole to the shank. As the pressure lever 7 is actuated, the dog 12 engages one of the teeth 11 and serves to maintain the arm 18, ma- 30 terial 20 and sole in stressed condition. After a sufficient amount of time has elapsed to per- 30 mit a setting of the cement the dog 12 is re- 35 leased from the teeth 11 and the lever 7 oper- 35 ated to release the pressure from the arm 18, thus permitting withdrawal of the arm 18 from the arm 6 and subsequent removal of the shoe 35 from the last.

40 From the foregoing it will be apparent that my device provides a simple and efficient means for exerting a desired amount of pressure on the shoe to hold the shank and sole together during 40 the cementing operation thereof, thus eliminat- 45 ing the use of nails previously employed to secure the parts together.

45 It is to be understood that the outer periphery of the arcuate section 10 is formed eccentric in 45 relation to the pivot 8 whereby to increase the pressure on the arm 18 as the handle 15 is moved downwardly towards the last 16.

50 What I claim is:

A press of the class described, comprising, a 50 standard of substantially arcuate formation in elevation adapted for detachable mounting on a support member, said standard fashioned in intermediate the ends thereof with an opening for receiving one end of a pressure arm, a pressure 55

arm mounted within said opening and adjustable forwardly and rearwardly relative to said standard and capable of limited vertical rocking movement with relation thereto, a pressure cam pivoted to one of the ends of said standard for contacting and exerting pressure on the upper side of said pressure arm, a lever fashioned to said cam whereby to actuate said cam relative to said pressure arm, a dog pivoted to 5
10 said standard adjacent said cam for maintaining

said cam in adjusted position, a last subjacent said pressure arm for receiving thereon a shoe, and resilient means secured to the underface of said pressure arm for engagement with said shoe whereby to maintain parts of said shoe under 5 pressure during a cement setting operation when said cam is actuated to pressure applying position relative to said pressure arm.

MAX W. MILLER. 10
